UNITED STATES PATENT OFFICE.

GEORGE W. JOHNSTON, OF ST. JOSEPH, MISSOURI, ASSIGNOR OF TWENTY-SEVEN ONE-HUNDRED-AND-FORTIETHS TO HORACE F. WHITEFORD, OF ST. JOSEPH, MISSOURI, AND CHARLES J. HUNT, OF DELOIT, IOWA.

WATER-WHEEL.

SPECIFICATION forming part of Letters Patent No. 708,715, dated September 9, 1902.

Application filed December 12, 1901. Serial No. 85,638. (No model.)

To all whom it may concern:

Be it known that I, GEORGE W. JOHNSTON, a citizen of the United States, residing at St. Joseph, in the county of Buchanan and State 5 of Missouri, have invented certain new and useful Improvements in Water-Wheels; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 My invention is designed to utilize the waters of natural or artificial streams by a wheel and attached mechanism so constructed that it will offer the least possible resistance against the stream, yet possess the largest 20 degree of power and speed, that will make it possible to dispense with the usual framework and masonry and render the wheel less liable to become entangled by floating logs or other floodwood or debris, and that will permit 25 the wheel to be readily submerged to any depth desired.

In the drawings, Figure 1 is a top view of the shaft, hub, hub-sockets, arms, folding leaves, and hinges. Fig. 2 is a perspective 30 of the mechanism for raising and lowering the wheel and forming connection with the bank of the stream and showing the wheel sunk to the preferable depth, the line $\alpha\alpha$ indicating the surface of the water. Fig. 3 is a detail of the raising and lowering gear, the shaft, and the hub broken away into two pieces, the clutch-teeth and one set of arms broken away, the collar, the set-screws, the keys, and a keyway. Fig. 4 is an end view 35 of an arm, hinge, and the attached leaves spread in position to receive the current of the stream. Fig. 5 is a side view of the hinges, arm, and clamp, showing the leaves spread out, but partly broken away, to receive the 40 force of the stream. Fig. 6 is an end view of an arm and hinge with the attached leaves folded together in their normal position, and Fig. 7 is a detail end view of an arm with the 45 hinges removed and showing a clamp thereon held in position by bolts or screws.

Similar letters refer to similar parts throughout the several views.

In the drawings, A A represent two timbers for connecting with the bank, broken away at the shore ends and supported by a pile A'. 55

B B are bearings, and B' a casting bolted to the timbers.

C is a bevel-gear, and C' the drive-shaft (shown broken away) for transmitting power 60 to a plant.

D is the worm-gear, and D' the wheel and shaft for operating the same.

E represents a pile driven into the bed of a stream and provided with an iron socket E', rigidly set in its top end, as shown by dotted 65 lines in Fig. 2.

F is an iron shaft having its bottom end tapered to a form adapted to operate in socket E', which shaft end is also shown by dotted lines in Fig. 2. Its top end revolves 70 in bearing B.

H is a hub on shaft F. This hub is provided with sockets H' H', which sockets carry arms I I. These arms carry folding leaves I' I'. I construct my device with at least 75 three sets of arms, as shown, each set consisting of at least six arms and each arm carrying two leaves. These leaves are of corresponding size, but the bottom sets are preferably made of heavy material, the top sets 80 of light material, and the middle sets of an intermediate weight, thus economizing material, as the lighter weight will serve at the upper part of the hub as well as the heavier. On account of the force of the water 85 in the bottom of the stream being greater than the force thereof at the surface of the water and at intermediate points it will be readily seen that it is desirable to vary the weight of the leaves in proportion to the altitude which they occupy on the hub, and I reserve to myself the right to regulate the number of arms and leaves by the depth of the water. These folding leaves are constructed with a height of two feet and width of six 95 feet, or about that proportion. By constructing my device with narrow but high leaves and providing it with six instead of two sets of arms and leaves I am enabled to materially reduce the weight of each arm and leaf, 100

gain power and speed, and largely obviate the danger incident to leaves carried by arms projecting a long distance from the shaft into the stream. These folding leaves are connected with the radially-projecting arms I I by means of hinges J J. The arms are provided with depressions or notches i i. Each pair of hinges is provided with a clamp J', which is fitted into depressions i i and the two parts of which are held firmly on the arm by means of bolts or screws d d. Each clamp is provided with two lugs j j, which receive the back of the hinge-straps when the leaves are spread out, thus assisting in preventing absolutely the leaves being pressed back beyond a vertical position and also holding the leaves in that position until each pair of leaves has fulfilled its function and are folded together automatically by the current as they pass around to be again spread out vertically by the force of the stream. Short projection b on each clamp prevents the folded leaves passing their respective centers. A collar K fits loosely around hub H below a flange h at the top thereof, and it is held in position by a rod k, which forms vertically-movable connection with pile A'. Cables L L, forming connection between loops l l on said collar and the worm-gear, serve in raising and lowering the hub, arms, and leaves. Shaft F and hub H are provided with keyways O O and keys O' O', said keyways and keys extending up to a line slightly below the clutch-teeth. The lower part of the hub Q is made separate and held stationary on the shaft at the desired depth by means of set-screws P P, the parts being provided at point of separation with clutch-teeth t t. Said set-screws P P are supplemental. Either said keys or said screws or said keys and screws may be used in manipulating the device. A cap R, rigidly fastened at the bottom of shaft F, is adapted to close socket E' from the entrance of sand or other impediment. By turning wheel D' in the proper direction for winding cables L L that portion of the hub which carries the arms and leaves will be lifted, thereby parting the hub at the clutch. This will result in the motion of the shaft being stopped. By reversing wheel D', unwinding the cables, the hub will be lowered into clutch connection, thereby starting the shaft and setting the gear in motion and permitting the transmissal of power to the point desired.

My device can be readily placed on a barge anchored and operated in the channel of a stream and used for pumping sand or water generating an electric current, or similar work.

What I claim, and desire to secure by Letters Patent, is—

1. In a wheel for utilizing the current of a stream, its supporting pile and socket, the shaft and its bearings, the hub and its radially-projecting sets of sockets, the arms carried by said hub-sockets, the duplicate leaves

hinged to each arm and the clamps and lugs to support said leaves when spread out against the current of the stream, substantially as described and for the purposes set forth.

2. In a water-wheel a shaft set vertically, a hub adapted to revolve on said shaft and provided with arms and leaves, the adjustable lower part of said hub having clutch connection therewith, and adapted to be rigidly fastened to said shaft and to support the upper part of the hub, the collar on the hub and the cables forming connection between said collar and the gear and adapted to raise the hub out of clutch connection thereby stopping the revolutions of the shaft, or to lower the hub into clutch connection thereby setting the mechanism in motion, substantially as described.

3. The combination with a water-wheel of the hinges upon an arm each having its strap rigidly attached to the back of the leaf, the depressions in the arm, the clamps the two parts of each of which fit into said depressions, the lugs on said clamps extending horizontally in opposite directions across the backs of the hinge-straps and leaves preventing the leaves being crowded back of their respective centers by the pressure of the current of the stream, substantially as described and for the purpose specified.

4. In a wheel for utilizing the power in the current of a stream, the vertically-set shaft adapted to revolve in the piling or support thereunder, the hub carried on said shaft, the flange at the top of said hub and the loosely-fitted collar thereunder adapted to serve in lowering and hoisting the hub, the rod attached to said collar and adapted to form connection with the shore-piling, together with the cable connection between the collar and the gearing, substantially as described and for the purpose specified.

5. The combination with the shaft and hub and lower member of said hub of a water-wheel, of triple sets of arms and leaves the sets being arranged vertically one above another with leaves of heaviest weight in the bottom set and lightest weight in the top set, substantially as described.

6. In a wheel for utilizing the power of the current of a stream the combination with the shaft and its hub, of the lower member of said hub, of the clutch connection between said hub and its lower member, of the keyways and keys below such clutch connection for attaching said lower part of the hub immovably to the shaft at the depth of water desired, of the set-screws to aid therein, substantially as described and for the purpose specified.

7. In a water-wheel the combination with the arms provided with depressions and the leaves and the hinges attached thereto, of the clamps adapted to fit into said depressions in the arms, the lugs on said clamps to prevent the leaves passing back of their respective centers and the projections on said

clamps to prevent said leaves passing forward of their centers or coming into actual contact, substantially as described.

8. The combination in a water-wheel of the upper bearing, cables and gearing for the purpose set forth, and pile E, with the vertical shaft, the hub thereon and its horizontally-projecting arms and sets of leaves of differing weights set vertically above each other, the lower member of the hub adapted to form clutch connection with said hub, the

socket in said piling and the cap at the bottom of the shaft to prevent the filling of the socket set with sand, substantially as described.

In testimony whereof I affix my signature in presence of two witnesses.

GEORGE W. JOHNSTON.
